United States Patent

Des. 238,549
Patented Jan. 27, 1976

238,549

DOOR HANDLE

Jean Arnold Fischer, Hjallese, Denmark, assignor to Daemps A/S, Knarreborg, Denmark

Filed Oct. 2, 1973, Ser. No. 402,787

Term of patent 14 years

Int. Cl. D8—06

U.S. Cl. D8—168

FIG. 1

FIG. 2

FIG. 3

FIG. 5

FIG. 4

FIG. 6

FIG. 1 is a perspective view of a door handle showing my new design;

FIG. 2 is a front elevation view of FIG. 1;

FIG. 3 is a perspective view of an embodiment of FIG. 1;

FIG. 4 is a front elevation view of FIG. 3;

FIG. 5 is a perspective view of another embodiment of FIG. 1; and

FIG. 6 is a front elevation view of FIG. 5.

I claim:

The ornamental design for a door handle, as shown and described.
